UNITED STATES PATENT OFFICE.

VICTOR I. ZACHERT, OF SAN FRANCISCO, AND PIERRE A. BRANGIER, OF AGNEW, CALIFORNIA, ASSIGNORS OF ONE-THIRD TO VICTOR G. BONALY, OF SAN FRANCISCO, CALIFORNIA.

APPARATUS FOR EXTRACTING PRECIOUS METALS.

1,160,485.

Specification of Letters Patent.

Patented Nov. 16, 1915.

Application filed June 25, 1914, Serial No. 847,233. Renewed April 20, 1915. Serial No. 22,717.

To all whom it may concern:

Be it known that we, VICTOR I. ZACHERT, a citizen of the United States, and resident of the city and county of San Francisco, State of California, and PIERRE A. BRANGIER, a citizen of France, residing at Agnew, county of Santa Clara, State of California, have invented new and useful Improvements in Apparatus for Extracting Precious Metals, of which the following is a specification.

This invention relates to an apparatus for extracting precious metals.

In every case in the metallurgy of precious metals the first step taken, when devising a method for its economic treatment, is to determine its amenability to the well-known amalgamation process. When the precious metals exist in a fairly coarse condition so that gravity will overcome the force of buoyancy, amalgamation is not absolutely necessary to obtain a profitable recovery, but the greater portion of precious metals, as found in nature, consist of very small particles, and for this reason other means than gravity for its separation from the ore must be resorted to. This can be most economically attained only by amalgamation. The physical condition of the particles of precious metals has, however, a great influence on its adaptability to the amalgamation process; that is, the metals may be of a flour-like or flaky nature, or, in other words, sufficiently buoyant to pass through an amalgamator with the wash water without ever coming in contact with the plates or the mercury contained therein. Again, the metal particles may be so oxidized, or, as is universally termed, "rusty," as to prevent them from uniting with the mercury.

One of the objects of the present invention is to overcome these difficulties, and to provide a simple, substantial, easily operated amalgamator which is capable of offering a large active amalgamating surface in which the pulp is automatically advanced, without contamination with the ingressing pulp, in such a manner that every metal particle will be given ample opportunity to come in contact with the plates or mercury which are used to form the amalgam.

Another object of the invention is to provide means for extracting any metals which

may be contained in solution, and also to remove any oxids or foreign substances inert to amalgamation, and to continuously produce alkali amalgam, such as sodium or potassium, by electrolytic action. Further objects will hereinafter appear.

The invention consists of the parts and the construction and combination of parts as hereinafter more fully described and claimed, having reference to the accompanying drawings, in which—

Figure 1 is a central longitudinal section through the amalgamator. Fig. 2 is a cross section of same.

Referring to the drawings, A indicates a horizontally positioned cylinder of considerable length mounted upon rollers 2 and 3 and adapted to be given a continuous rotary movement by any suitable means, or, as here shown, by gears 4 and 5. Formed on the interior surface of the cylinder, or secured thereto, is a continuous spiral flange 6 which forms a spiral flume or way extending from end to end of the cylinder and which is provided for the purpose of feeding the material to be treated therethrough.

One end of the cylinder is closed by a head 7, and a plurality of openings 8 is formed at the same end through which the material is permitted to discharge into a launder 9 which connects with a trap or like device not here shown. The other end of the cylinder is partly open, as indicated at 10, and extending through said opening is a feed launder 11 through which the material to be treated is delivered. Mounted interior of the cylinder and running practically through the entire length of same, in a parallel position with relation to the interior surface of the cylinder, is a plurality of anodes 12. The outer ends of the anodes 12 are carried by the head 7 and are suitably insulated from same and secured to their extreme outer ends, outside of head 7, is a contact ring 13. The other ends of the anodes may be suitably supported, or, as here shown, carried by bracket members 14 which are insulated from the cylinder. Secured exterior of the cylinder, near the discharge end, is a second contact ring 15, and engaging with the rings 13 and 15 is a pair of brushes 17 and 18 which complete a

circuit between a suitable source of electric supply, such as a dynamo or battery, not here shown.

In operation, it is preferable to mix the material with an alkali solution, such as sodium or potassium hydrate. This, together with the material, is delivered through the feed launder 11 into the front end of the cylinder and is from this point gradually advanced by means of the continuous spiral flange 6. The interior surface of the cylinder may be coated with mercury, as are the surfaces of the spiral flange, or a suitable amount of free mercury may be admitted with the pulp or otherwise delivered to the cylinder. The continuous rotary movement of the cylinder will cause the pulp and solution to be partly carried up on one side until the angle for support becomes too great. The pulp and solution will thus constantly be turned over and over and will regularly progress from one spiral to the next, at the same time submerging some of the anodes. An electrolytic action is thus set up in the solution which causes the desired decomposition to take place, causing any metals to deposit in the mercury or on the mercury-coated interior face of the cylinder which acts as a cathode. It also liberates the alkali metal and permits this to amalgamate with the mercury. Metallic sodium or potassium, when added to mercury, produces an amalgam of greatly increased activity or amalgamating power. Gold which is highly oxidized or coated with a foreign substance inert to amalgamation by ordinary treatment will in this instance immediately become amalgamated. Even platinum and metals of the platinum group will likewise be attracted by this highly active mercury combination. Furthermore, the constant turning over of the pulp, caused by the rotary movement of the cylinder and the advancing movement of the spiral flange, gives every metal particle an opportunity to be brought into contact with the free amalgam or amalgamating surfaces. Pregnant solutions may also be successfully handled by the present form of apparatus as the electrolytic action will cause the decomposition which will liberate the metal in solution and cause it to deposit on the cathode. A highly efficient amalgamator is thus produced in which a large amalgamating surface is presented and over which the material is constantly turned and advanced. The continuous forward advancing movement of the material or solution furthermore prevents any contamination with the ingressing pulp. The gangue or solution discharging through the openings 8, together with any amalgam which may escape therefrom, may be conveyed by the launder 9 to a trap, sump, or to any other suitable apparatus where the different materials may

be separated, if needed, and from where the solution may again be returned, when used. A continuous operation is secured and practically no sodium or potassium is lost, as all free alkali decomposed by the electrolytic action is again absorbed by the solution when freed from the amalgamator. 70

The materials and finish of the several parts of the amalgamator, together with the construction and position of the anodes, may be such as the experience and judgment of the manufacturer or operator may dictate. We also wish it understood that the cylinder may be jacketed, as indicated at 24, to permit circulation of a heating fluid, such as steam, or the like, as it has been found very beneficial in the treatment of certain solutions. 75

Having thus described our invention, what we claim and desire to secure by Letters Patent is— 80

1. In an amalgamator, a horizontal cylinder, a continuous spiral flange on the interior of the cylinder secured to the inner circumference thereof, said flange having 90 series of apertures which register longitudinally of the cylinder, and an anode passed through each series of apertures and being insulated from the flange. 95

2. In an amalgamator, a horizontal cylinder having a head at each end thereof, the head at the front end of the cylinder having a feed opening, a continuous spiral flange on the interior of the cylinder secured to the inner circumference thereof, said flange 100 having series of apertures which register longitudinally of the cylinder, an anode passed through each series of apertures and being insulated from the flange, said anodes having their front ends spaced from the 105 front cylinder head and having their rear ends passed through the rear cylinder head, and a contact ring secured to the rear ends of the anodes on the exterior of the cylinder, said cylinder having a peripheral discharge 110 at its rear end on the inner side face of the rear cylinder head. 110

3. A continuous electrical amalgamator comprising in combination a horizontally disposed rotatable cylinder having a continuous spiral flange on the interior by which the material is progressed continuously from one end of the cylinder to the other, an anode in conjunction with the spiral flange and insulated therefrom and 115 extending substantially the length of the interior of the cylinder, the cylinder forming a cathode, and electrical connections whereby the circuit is completed through the submerging fluid in the bottom of the cylinder, 120 said cylinder having an infeed at one end and a discharge at the other. 125

4. The combination in a continuous electrical amalgamator of a horizontal cylinder having a head at each end, the head at the 130

front end having a feed opening, said cylinder having peripheral discharge openings at the other end, means for causing infed material to progress gradually from the feed end to the discharge end on the rotation of the cylinder, and an electrode within the cylinder adapted to be submerged on the rotation of the latter, the cylinder forming the other electrode, substantially as described.

In testimony whereof we have hereunto 10
set our hands in the presence of two sub-
scribing witnesses.
